(57) **CLAIM**

The ornamental design for a pressure regulator for respiratory machines, as shown and described.

DESCRIPTION

FIG. 1 is a top, front right perspective view of a pressure regulator for respiratory machine.

FIG. 2 is a top, front left perspective view of the pressure regulator for respiratory machine shown in FIG. 1.

FIG. 3 is a front view of the pressure regulator for respiratory machine shown in FIG. 1.

FIG. 4 is a rear view of the pressure regulator for respiratory machine shown in FIG. 1.

FIG. 5 is a left side view of the pressure regulator for respiratory machine shown in FIG. 1.

FIG. 6 is a right side view of the pressure regulator for respiratory machine shown in FIG. 1.

FIG. 7 is a top view of the pressure regulator for respiratory machine shown in FIG. 1; and,

FIG. 8 is a bottom view of the pressure regulator for respiratory machine shown in FIG. 1.

The broken lines appearing in FIGS. 1-8 show portions of the pressure regulator for respiratory machine that form no part of the claimed design.
